HEATING APPARATUS

Lee Wilson, Cleveland, Ohio

Application May 2, 1936, Serial No. 77,551

2 Claims. (Cl. 257—262)

This invention relates to the art of heating and, particularly to indirect heating, e. g., that which is effected by passing hot fluids through a conduit and by radiation from the latter to the point or object to be heated.

A specific application of indirect heating peculiarly subject to the difficulty which it is the object of the present invention to overcome, is found in annealing covers of the radiant tube type such as described and claimed in my U. S. Patent No. 1,952,402 although it will be recognized that this problem is general and the applicability of the present invention is correspondingly broad. While the invention will be described with particular reference to furnaces or annealing covers, this is merely by way of illustration and does not constitute a limitation upon the scope of the invention.

When it is attempted to heat a space or an object by passing hot fluids through a radiating tube or conduit, the natural result is that the temperature of the tube wall decreases progressively therealong from the point at which the hot gases are supplied thereto or generated therein. In other words, the hot fluids, such as combustion gases, cool gradually as they give up heat to the tube. In many cases, however, it is desired that the temperature of the tube remain substantially constant throughout its entire length, instead of presenting a so-called "hot spot" at the point of admission or generation of the heating fluid, and a progressively decreasing temperature from that point toward the discharge end of the tube. This problem is particularly acute in the process of annealing steel sheets in stacks, since the characteristics of the finished product depend largely on the temperatures to which they are heated during the annealing.

I have invented an apparatus whereby it is possible to obtain a greater uniformity in the temperatures at various points along the length of a radiant tube, even though the hot fluid supplying heat thereto is introduced or generated in a relatively confined space and transmitted therealong, gradually losing heat to the tube. In accordance with my invention, I restrict the flow of heat radially through the tube wall to varying degrees, the restriction being greatest adjacent the point of introduction or generation of the hot fluids, and decreasing gradually along the length of the tube from that point toward the discharge end. I thus counteract the natural tendency for the tube to radiate the greater portion of the heat from the zone of its length traversed by the gases while at their highest temperature, the restric-

tive effect being tapered off, along the length of the tube, to permit greater heat radiation from points at which the gases traversing the tube are somewhat cooled from their original temperature.

My invention, in one embodiment, takes the form of a plurality of thickening bands disposed about the radiant tube at varying intervals. The bands are closest together at the points of introduction or generation of the hot fluid, the spacing therebetween increasing gradually toward the discharge end of the tube. The thickening bands provide relatively short zones of increased thickness and thereby restrict transmission of heat radially of the tube wall.

For a complete understanding of the invention reference is made to the accompanying drawing illustrating several forms which the apparatus of my invention may take.

In the drawing:

Figure 1 is a view partly in section and partly in elevation showing a radiant tube with thickening bands applied externally thereof;

Fig. 2 is a view similar to Fig. 1 showing a modified form;

Fig. 3 is a view similar to Fig. 1 showing thickening bands disposed internally of the tube; and

Fig. 4 is an axial section through a heating tube showing thickening bands as illustrated in Fig. 2 disposed internally of the radiant tube.

Referring now in detail to the drawing, a heating tube 10 is provided at the end of a burner 11. Fuel and air for combustion are delivered to the burner, by any known means (not shown). The resulting combustion evolves considerable quantities of hot gases in a relatively short portion of the tube length just beyond the burner. As the gases expand because of the heat generated, they flow along the tube toward the discharge end thereof indicated generally at 12. The fuel and air for combustion, of course, must be delivered under a pressure greater than that created in the tube by the expansion of the combustion gases.

Thickening bands 13 are disposed at intervals along the length of the tube 10. In Fig. 1 these bands are simply annular rings and may be of any desired shape or material and secured to the tubes in any convenient manner. The dimension of the bands axially of the tube 10 is preferably several times (i. e., two or three times) the dimension thereof radially of the tube. The bands 13 provide relatively short zones of increased thickness. This increased thickness, together with the film of air or gas between the bands and the

tube, causes a reduction in the flow of heat radially of the tube wall, as compared to the rate of flow through the portions of the wall not covered by the bands.

5 The spacing between the bands increases in proportion to the distance along the tube from the burner 11. As the hot gases travel along the tube and are cooled as a result of giving up heat thereto, a greater proportion of tube surface un-
10 covered by the thickening bands is provided to permit transmission of about the same amount of heat per unit length as in the tube sections nearer the burner. The temperature of the tube at all points therealong is thus maintained substan-
15 tially constant. At the discharge end, the entire surface of the tube may be left uncovered.

By this arrangement, I limit the amount of heat transmitted through the tube walls for radiation therefrom adjacent the burner where the 20 combustion gases are hottest. The temperature of the tube wall adjacent the burner is thus made more nearly equal to the temperature of points of the tube wall remote from the burner and a more uniform heating effect is thereby obtained.
25 It is assumed, of course, that the heat radiated by the tube is absorbed by the material or space being heated substantially uniformly at all points along its length, so that the control of the rate of heat flow through various portions of the wall 30 made possible by the invention, actually determines the temperatures of the tube at various points along its length.

Figure 2 shows a slight modification in which the tube 10 is provided with a helical wrapping of strip, wire, rod or the like, indicated generally at 35 14. The turns of the wrapping are spaced more closely adjacent the burner 11 and at points remote therefrom, the spacing between turns increasing gradually almost in proportion to the 40 distance from the burner. The result produced by the structure shown in Fig. 2 is substantially the same as that of the arrangement of Fig. 1, about the only difference being that the successive turns of the wrapping form helical bands which, 45 instead of being independent, are connected each to its neighbors.

Figure 3 illustrates a heating tube similar to that of Fig. 1 except that the thickening bands

13' are disposed interiorly of the tube instead of exteriorly.

Figure 4 likewise shows a tube similar to that of Fig. 2 except that the helical wrapping 14' is disposed inside the tube. 5

It will be apparent from the foregoing description that the invention makes it possible to attain a substantially uniform external temperature along all points of the heating tube despite the fact that the heating gases are hottest adjacent the burner and cooled progressively as they flow therefrom along the tube. By properly spacing the thickening bands, a considerable range of average external tube temperatures may be obtained. The invention utilizes the principle that 10 the average temperature along the outside of the tube is dependent upon the heat transmitting characteristics of the wall section at various points therealong. 15

While I have illustrated and described herein 20 but one embodiment of the invention with certain modifications, it will be recognized that changes in the construction described may be made, within the scope of the appended claims, without departing from the spirit of the invention. In the claims, the term "bands" is to be 25 defined as including both the separate bands of Figures 1 and 3 and the successive turns of a helix as shown in Figures 2 and 4.

I claim:

1. In a heat exchange apparatus, a tube of substantially uniform diameter and wall thickness adapted to be heated by the passage of fluid therethrough, and thickening bands extending around the tube in spaced relation longitudinally thereof, the spacing between adjacent bands varying along the length of the tube, and the dimension of said bands axially of the tube being several times their dimension radially of the tube. 35

2. In a heat exchange apparatus, a tube of substantially uniform diameter and wall thickness adapted to be heated by the passage of fluid therethrough, and thickening bands extending around the tube in spaced relation longitudinally thereof, the spacing between adjacent bands varying along the length of the tube, the bands having a width greater than their thickness and disposed flatwise on the tube. 40 45

LEE WILSON.
